KERF-CUTTING MACHINE

William W. Sloane, Chicago, Ill., assignor to
Goodman Manufacturing Company, Chicago,
Ill., a corporation of Illinois

Original application March 19, 1943, Serial No.
479,717, now Patent No. 2,339,523, dated Janu-
ary 18, 1944. Divided and this application
December 15, 1943, Serial No. 514,321

9 Claims. (Cl. 262—30)

This invention relates to improvements in kerf-cutting machines and more particularly relates to an improved kerf-cutting machine of the room and pillar type which is adapted to cut a horizontal kerf in the mine wall.

This application is a division of application Se-
rial No. 479,717, filed March 19, 1943, now Patent
No. 2,339,523, dated January 18, 1944.

The principal objects of my present invention
are to provide a new and improved fluid control
for a kerf-cutting machine of the class described,
so arranged that the machine can be controlled
from either side thereof.

Other objects of my invention will appear from
time to time as the following specification pro-
ceeds and with reference to the accompanying
drawings wherein:

Figure 1 is a plan view of a kerf-cutting ma-
chine constructed in accordance with my inven-
tion, with certain parts broken away and certain
other parts shown in horizontal section;

Figure 2 is an enlarged detail fragmentary plan
view of a portion of the machine shown in Fig-
ure 1, illustrating certain details of the support
for one of the fluid pressure jacks;

Figure 3 is a partial fragmentary front end
view of the kerf-cutting machine embodying my
invention, with certain parts shown in substan-
tially transverse section;

Figure 4 is an enlarged fragmentary view of
the front end of the machine, with certain parts
broken away and certain other parts shown in
substantially longitudinal section;

Figure 5 is an enlarged fragmentary detail par-
tial transverse sectional view of the machine, il-
lustrating certain details of the planetaries for
driving the feed drums of the machine, and cer-
tains of the control means for said planetaries;

Figure 6 is an enlarged detail view illustrating
certain details of the control means for one of
the planetaries, not shown in Figure 5;

Figure 7 is a partial fragmentary transverse
sectional view, illustrating the drive to the fluid
pumps which supply fluid under pressure to the
machine;

Figure 8 is a fluid diagram illustrating the
fluid pressure system, for controlling operation
of the machine;

Figure 9 is a longitudinal sectional view taken
through one of the control valves for controlling
operation of one of the feed drums for the ma-
chine, with the valve rotor shown in full;

Figure 10 is a sectional view taken substan-
tially along line 10—10 of Figure 9;

Figure 11 is a sectional view taken substan-
tially along line 11—11 of Figure 10;

Figure 12 is a sectional view taken substan-
tially along line 12—12 of Figure 9;

Figure 13 is a sectional view taken substantially
along line 13—13 of Figure 12; and

Figure 14 is a fragmentary plan view of the
control valve, illustrating certain details of the
spring connections to the control handle, for hold-
ing the control handle in a predetermined posi-
tion when the hand is removed therefrom.

The invention illustrated in the drawings is
shown as being embodied in a top cutting kerf-
cutting machine of the room and pillar type.

15 Said kerf-cutting machine includes a main frame
10, having a horizontally extending cutter bar
11 projecting from the front end thereof. Said
cutter bar has a cutter chain 12 guided for orbital
movement thereabout, and as herein shown, is
20 mounted in a recessed cuttings passageway on
the top side of said main frame. A motor 13 is
mounted at the rear end of said main frame and
forms a means for driving said cutter chain about
25 said cutter bar, through a sprocket 14 meshing
with said cutter chain and herein shown as being
splined on the upper end of a vertical shaft 15,
suitably journaled in said main frame (see Fig-
ure 4).

A base plate 16 having upturned sides and ends
30 and adapted to be slidably movable along the
ground, on its bottom, during the cutting oper-
ation, forms a mounting for said kerf-cutting ma-
chine on the ground. The kerf-cutting machine
is mounted on said base for vertical adjustment
35 and for tilting movement with respect thereto by
means of three fluid pressure jacks 17, 17, two
of which are mounted at opposite sides of the
forward end of said base and the third of which
is mounted at the central rear end of said base,
40 to provide a three-point mounting for said kerf-
cutting machine on said base. The supporting
connection between said jacks and said kerf-cut-
ting machine will hereinafter be more clearly de-
scribed as this specification proceeds.

45 The drive connection from the motor 13 to the
shaft 15 and sprocket 14, for driving the cutter
chain 12 about the cutter bar 11, includes an
intermediate shaft 18 extending longitudinally of
the main frame 10 and journaled therein and
50 driven from said motor through a gear train in-
dicated generally by reference character 19. A
bevel pinion 20 on the forward end of said inter-
mediate shaft meshes with and drives a bevel gear
21 journaled on the vertical shaft 15, for rotat-
55 able movement with respect thereto. A sliding

clutch 22, herein shown as being a jaw clutch, is provided to selectively drive said shaft and sprocket from said bevel gear.

The feeding means for the machine includes a pair of winding drums 23, 23 rotatably mounted on opposite sides of the main frame 10. Each of said winding drums has a flexible cable 24 adapted to be wound thereon or payed off therefrom, and is adapted to be engaged by a friction band 25 for retarding rotation thereof, when disconnected from the drive motor 13, enabling either one of said winding drums to serve as a retarding means to control the travel of the machine across the coal face during the cutting operation.

The drive from the motor 13 to the winding drums 23, 23 includes a worm 27 on the intermediate shaft 18, which meshes with a worm gear 29 on a transversely extending sleeve 30. Said sleeve 30 is journaled in the main frame 10 and forms a drive means for a pair of coaxial planetary gear reduction devices indicated generally at 31, 31, arranged at opposite sides of said sleeve. The form of planetary gear shown herein is of the same general type commonly used in kerf-cutting machines, so need not be described in detail except to point out that planetary pinions 32 and 33 of different pitch diameters and mounted in a cage 34 for rotation together are meshed respectively with internal gears 35 and 36 (see Figure 5).

The internal gear 36 has a hub 37 keyed on a driven shaft 39. The cage 34 has a driven portion 40 which encloses the internal gear 36 and which has a friction band 41 extending thereabout, for holding said cage from rotation. A similar friction band 42 surrounds and is adapted to hold the internal gear 35 from rotation. The planetary pinions 32, 32 are meshed with and driven from a sun gear 43 on the sleeve 30, and when the friction band 41 is loose so the cage 34 may freely rotate, and the friction band 42 is tightened to hold the internal gear 35 from rotation, said planetary pinions will orbitally move about said internal gear, to drive the shaft 39 at a slow frictionally controlled speed through the internal gear 36, keyed on said shaft. When the friction band 42 is loosened and the friction band 41 is tightened, the cage 34 will be held from rotation and the shaft 39 will be driven at a frictionally controlled high speed.

The driven shaft 39 is journaled in a side wall 44 of the main frame 10 and has a pinion 45 keyed on its outer end, which meshes with an internal gear 46, journaled on its hub on a stub shaft 47, mounted in and projecting outwardly from said main frame. The winding drum 23 is freely mounted on an outwardly projecting hub 49 of said internal gear and has a pin 50 mounted therein for transverse slidable movement with respect thereto. The inner end of said pin is adapted to engage any one of a plurality of apertures 51, 51 formed in the web of said internal gear, to form a selective drive connection from said internal gear to said winding drum.

The friction bands 41 and 42 are engaged with their respective drums, to hold the cage 34 or internal gear 35 from rotation by means of fluid cylinders 55 and 56, having pistons 59 and 60 movable therein. Each set of said cylinders is mounted in a frame 61, disposed above and extending across its respective planetary 31. The piston 59 has a plunger 62 mounted therein for limited slidable movement with respect thereto. Said plunger is slidably guided in a lower wall

57 of said frame and has engagement at its outer end with an abutment member 63, projecting outwardly from one end of the friction band 42. The opposite end of said friction band has a lug 53 thereon, which abuts a notched portion of an inner wall 54 of said housing (see Figure 4). A pair of concentric compression springs 64 and 65 encircle said plunger and are interposed between the inside of said piston and a collar 66, mounted on said plunger, to serve as a cushioning means when pressure is applied on said piston to engage said friction band with its associated drum. Said springs are provided to provide elasticity in said friction band, to prevent a sudden gripping of the friction drum by said friction band as fluid is supplied to said cylinder 55 and to enable said band to be uniformly engaged with said friction drum by said fluid cylinder and piston. Said springs also serve to return the pistons 59 and 60 to the head ends of their respective cylinders, and to empty fluid from said cylinders when fluid pressure is relieved therefrom.

In a like manner, a plunger 67 is mounted in 25 the piston 60 for limited slidable movement with respect thereto and is slidably guided in the wall 57 of the frame 61. The ends of said plunger opposite from said piston abuts a lug 68 projecting outwardly from the free end of the friction band 41. A pair of coaxial compression springs 70 and 71 encircle said plunger and serve as a cushioning means, effective when applying said friction band through the associated piston 60, and permitting uniform engagement of said friction band with its associated drum. The fluid pressure system for selectively controlling the admission and release of fluid under pressure to and from said cylinders and pistons will hereinafter be more fully described as this specification proceeds.

Each of the three jacks 17, 17, mounted on the base 16 and forming a vertically adjustable and tilting support for the cutting element, includes a fluid cylinder 74 having a piston 75 extensible 45 therefrom. Said cylinders are secured to said main frame in a suitable manner clearly disclosed in my application Serial No. 479,717, of which this is a division, and not herein shown or described since it is no part of my present invention.

The lower ends of the pistons 75, 75 are suitably pivoted to the base 16 for universal pivotal movement with respect thereto in a manner clearly disclosed in my aforementioned parent application, and no part of my present invention is not herein shown or described in detail.

When fluid under pressure is simultaneously admitted to the three cylinders 14, 14 at the same pressure, the cutter bar 11 will be elevated in a 60 plurality of parallel planes and tilting of said cutter bar may be effected by admitting fluid under pressure to any of said cylinders while the other cylinders are stationary, or by cutting off the flow of fluid to any one or more cylinders, or 65 by releasing fluid pressure therefrom, while the entire cutting element is being elevated or lowered by the other cylinders.

Referring now in particular to the fluid pressure system and the means for controlling the admission and release of fluid to the cylinders 55, 55 and 56, 56, for controlling operation of the planetaries 31, 31, and to the fluid cylinders 74, 74, for controlling the elevation or tilting of the cutter bar 11, three fluid pumps 91, 92 and 93 are provided. Said fluid pumps are shown as being

of a reversible type so as to provide pressure in the fluid system when the motor 13 is rotating in a forward or reverse direction, and are herein shown as being mounted in a casing 94 and as being driven from a common drive shaft 95.

The drive to the pumps 91, 92 and 93 from the motor 13 includes a pinion 96 driven from the gear train 19 and meshing with and driving a gear 97 on the pump drive shaft 95 (see Figure 7).

Fluid is supplied to the pumps 91, 92 and 93 through a suction line 100 leading from a fluid storage tank 101. Said suction line 100 is connected to opposite sides of each one of the pumps 91, 92 and 93, for supplying fluid thereto, when the motor 13 is rotating in a forward or reverse direction. Check valves indicated generally by reference characters 104, 104 and 105, 105 are provided within said casing, for each pump, to control the direction of the flow of fluid to each pump, when the direction of rotation of the pump is reversed. Said check valves serve a well known function and may be of any well known form and are no part of my present invention, so are not herein shown or described in detail.

Fluid is supplied to the rear fluid cylinder 14 by means of the fluid pump 91 through a pressure line 106 leading from said pump. A relief valve 107 is connected in said pressure line, to relieve pressure from said pressure line upon overload. Said relief valve is herein diagrammatically shown as being mounted within the casing 94, but may be placed outside of said casing, if desired.

The pressure line 106 leads to a valve 110 in a valve manifold 111. Said valve is diagrammatically shown as being a piston valve of a well known form and is normally in a position to release fluid to the return. When said valve is in the position shown in Figure 8, which is the position said valve will assume when the hand is removed from its control lever, fluid will flow from the line 106 through a passageway 112 to a chamber 113. Fluid will then flow through a hollow piston 114 of said valve, through a passageway 115 in said valve manifold, to return to the tank 101 through a return line 116. When said valve 110 is in a depressed position, the piston 114 will block the passageway 112, and fluid under pressure will flow through a pressure line 117, a non-reversible check valve 118, a pressure line 119, to the rear elevating cylinder 14, for supplying fluid under pressure thereto. When it is desired to release pressure from the cylinder 14, the piston 114 is moved in an upward direction to uncover a passageway 120, leading to the chamber 113 and directly connected with the pressure line 119. When said valve is in this position, the passageway 112 will also be open and fluid will pass through the pressure line 119, port 120, through the hollow piston 114, passageway 115, and return line 116, to the tank 101. When the hand is removed from the control handle for said valve, the piston 114 is moved to the neutral position shown. The passageway 120 will then be closed and pressure will be held in the fluid cylinder 14 through the check valve 118.

In a like manner, the pump 92 is adapted to supply fluid under pressure to the forward right-hand cylinder 74. A relief valve 122 is provided in the pump casing and is connected between a pressure line 123 and the suction line 100. Said pressure line 123 leads to a valve 124, which is provided to control operation of the right-hand planetary 31. A pressure line 125 connects said valve 124 to a valve 126 on the opposite side of the machine from the valve 124. The valve 126

is like the valve 124 and is provided to permit operation of the planetaries 31, 31 from either side of the machine. Said valves 124 and 126 are so arranged as to be yieldably held in a neutral position, when the hand is removed from the associated control handle thereof, and to hold pressure on the desired planetary operating cylinder when in a neutral position, so fluid under pressure will pass through said valves to supply pressure to the associated forward jack jack cylinder 74, during operation of the machine, as will hereinafter more clearly appear as this specification proceeds. A pressure line 127 leads from the valve 126 to a valve 128 in the valve manifold 111. Said valve operates in the same manner as the valve 110 and is adapted to by-pass fluid from the pump 92 and valves 124 and 126, or to release fluid from the fluid cylinder 74 in the same manner as the valve 110, so will not herein be described in detail. A pressure line 130 leads from the pressure line 127 to the right-hand forward fluid cylinder 74, for supplying fluid under pressure thereto. A non-reversible check valve 131 is provided in said pressure line to hold pressure in said cylinder and to permit fluid under pressure to pass therein when the valve 128 is depressed to close the passageway to return. A return line 132 is connected with the pressure line 130, on the pressure side of the check valve 131, to permit the release of fluid pressure from said right-hand cylinder 74 through said valve 128.

The left-hand cylinder 74 is supplied with fluid under pressure from the pump 93. A relief valve 137 is provided for said pump. A pressure line 133 leads from said pump to a valve 134, adjacent the valve 124, and provided for controlling the operation of the left-hand planetary 31. Said valve is herein shown as being a rotary valve like the valve 124. A pressure line 135 connects said valve 134 with a valve 136 on the opposite side of the machine, to supply fluid under pressure thereto. The valve 136 is like the valve 126 and is provided to permit operation of the left-hand planetary 31 from either side of the machine. Said valves 134 and 136, like the valves 124 and 126, are yieldably held in a neutral position when the hand is removed from the associated control handle thereof, to permit fluid under pressure to pass through said valves to the associated jack cylinder 74, during operation of the machine. A pressure line 139 leads from the valve 136 to a valve 140 in the manifold 111. Said valve is similar to the valves 110 and 129 and is provided to control the admission and release of fluid under pressure to the left-hand front cylinder 74 in the same manner the valves 110 and 129 control the admission and release of fluid under pressure to the rear and right-hand front cylinders respectively. A pressure line 141 is connected to the pressure line 139 and has a non-reversible check valve 142 therein. Said pressure line leads to the left-hand forward cylinder 74, for supplying fluid under pressure thereto. A return line 143 is connected to said pressure line and to the valve 140, to permit the return of fluid from the cylinder 74 to the tank 101 through the valve 140, when it is desired to release pressure from said left-hand forward cylinder.

It may be seen from the foregoing that each fluid pump 91, 92 and 93 is connected with a separate fluid cylinder 14, and that a separate control valve associated with each one of said pumps is provided to control the admission and release of fluid to said separate cylinders. It may fur-

ther be seen that fluid is supplied to said cylinders through non-reversible check valves, by blocking the flow of fluid to the return, so as to prevent any lag in operation of the respective jacks after operation of the control handles for the respective jack operating valves. Thus, any one cylinder may be operated independently of the others and the cutter bar may be tilted as it is being elevated or lowered, to readily position it for cutting.

In order that the fluid circuits to the cylinders 55, 55 and 56, 56 may be more clearly understood, the valve 134 illustrated in Figures 8 to 14 inclusive will now be briefly described, it being understood that said valve is of the same construction as the valves 124, 126 and 136. Said valve includes a valve rotor 175 rotatably mounted in a cylindrical chamber 176 formed in a valve casting 177. Said valve rotor is provided with a pair of spaced balancing passageways 178 and 179 extending therethrough, to balance the valve rotor when the pressure line is blocked by said rotor. Said passageways extend diametrically through said rotor in different angular directions. Said rotor is also provided with a pair of oppositely disposed milled fluid passageways 180, 180 extending across an outer portion thereof and in line with the balancing passageway 178. Said milled passageways 180, 180 are connected together by a plurality of passageways 181, 181 extending across the rotor and spaced from said balancing passageway 178, to permit the passage of fluid from one side of the rotor to the other (see Figure 10). Said rotor is likewise provided with a pair of oppositely disposed milled passageways 182, 182 in line with the balancing passageway 179. Passageways 183, 183 connect said milled passageways together (see Figure 12).

Fluid under pressure enters the valve 134 through the pressure line 133. Said pressure line is connected with a port 184 extending into the casing 177 parallel to the rotor 175 and opening into the chamber 176, in alignment with the passageways 180 and 182 (see Figure 11). Fluid is exhausted from said valve through a port 185 communicating with the exhaust line 135 and extending into said casing parallel to said rotor and opening into the chamber 176 in alignment with the passageways 180 and 182.

Fluid under pressure passes through the valve 134 and is conducted to the cylinder 56, for controlling operation of the high speed friction band for the left-hand planetary 31, when a control handle 187 for said valve is turned to an extreme position in a clockwise direction or to the left, as indicated in Figure 10. When said valve is in this position, fluid will enter the passageway 180 through the port 184. It will then pass through the passageways 181, 181 to the passageway 180, which communicates with a port 186 communicating with a pressure line 156. Fluid will thus be conducted through said port 186 and pressure line 156 to the cylinder 56, to charge said cylinder and apply the brake band 41 for the left-hand planetary in an obvious manner.

When the valve 134 is in this last named position, fluid will be exhausted from the cylinder 55 controlling operation of the low speed friction band 42 for the left-hand planetary 31 through a pressure line 153 leading from said cylinder and communicating with a port 188 in the valve casting 177. Said port opens into the chamber 176 in alignment with the passageway 182 in the rotor 175 (see Figures 12 and 13). Fluid will thus enter the passageway 182 and pass through the

rotor 175 through the passageways 183, 183 and leave said rotor through the exhaust port 185.

Thus in the extreme clockwise position of the control handle 187, the cylinder 56 for the left-hand speed planetary will be charged and the cylinder 55 for the low speed planetary will be discharged to cause the left-hand feed drum to be driven at a high positioning speed.

The valve rotor 175 and the passageways 180, 180 therein are so arranged, however, that when the valve handle 187 is turned in an opposite direction the port 186 will be blocked by said rotor until said rotor has been turned beyond a neutral position, and the port 188 will be open to exhaust during the same period of movement of said rotor. Also, during this period of movement of said rotor, when the port 186 has been blocked, fluid will pass directly through said valve from the pressure line 133 to the exhaust line 135.

When said valve rotor is in a neutral position the ports 186 and 188 will be blocked, to hold pressure on the cylinder 56 and to prevent fluid from entering the cylinder 55. In this position fluid will pass from the pressure port 184 through the passageways 182, 182 and out the exhaust port 185, where it may either be returned to the tank 101 or be used to operate the left-hand forward jack 17, in the hereinbefore described manner.

A pair of coil springs 190, 190 are provided to return the valve rotor 175 to any neutral position as soon as the hand is removed from the control handle. Said springs each have an outwardly turned inner end 191, which inner ends abut opposite sides of a lug 192 projecting downwardly from said control handle. The opposite ends of said springs abut spaced stops 193, 193 projecting outwardly from said valve casing (see Figure 14).

When it is desired to supply fluid under pressure to the cylinder 55, for applying the low speed left-hand friction band 42, the valve rotor 175 is turned in a clockwise direction to an extreme position to the right. In this position fluid will pass from the pressure passageway 184, the milled passageway 182, through the passageways 183, 183, the opposite passageway 182, and out through the port 188, to and through the pressure line 153, to charge said cylinder. In this position of said valve rotor and control handle, fluid will be exhausted from the left-hand high speed control cylinder 56 through the milled passageway 180, passageway 181, and exhaust passageway 185. As soon as the hand is removed from the control handle, however, said valve rotor will be returned to a neutral position, holding pressure on the low speed control cylinder 55 and permitting fluid to pass through the exhaust port 185 to operate the left-hand jack 17, during operation of the machine at a slow feeding speed.

When it is desired to release pressure from the cylinder 55 the control handle 187 is turned to the left to an intermediate position between an extreme open position and a neutral position. In a like manner, when it is desired to release pressure from the cylinder 56, said control handle is turned to the right to an intermediate position between an extreme position and a neutral position. Thus either cylinder 55 or 56 is charged by moving the control handle 187 in one direction and is discharged by moving said control handle in an opposite direction, and when one cylinder is charged, the other is discharged.

A drain line 194 is connected between the valves 134 and 136 and has connection with the return line 116 leading to the tank 101, to permit fluid

leaking by the rotors 175 of said valves to drain back to the tank 101.

The right-hand planetary 31 is operated by either of the valves 124 or 126 in the same manner the left-hand planetary is operated by the valves 134 or 136. When the valve 124 is in a full open position to one side of its neutral position, pressure will pass from the pressure line 123 through a pressure line 144 to the right-hand cylinder 55, to charge said valve and apply the right-hand low speed friction band. When the hand is removed from the control handle for said valve, said control handle and valve will go to a neutral position holding pressure in the pressure line 144 and cylinder 55, but permitting fluid to by-pass through said valve through the pressure line 125, the valve 126 and return to the tank 101, or to operate the right-hand jack 17, upon closing the valve 129, to prevent the return of fluid through said valve.

When the valve 124 is turned to an extreme position in an opposite direction, fluid under pressure will be admitted through said valve from the pressure line 123, through a pressure line 147, to charge the right-hand cylinder 56 and apply the high speed friction band for the right-hand planetary 31. When the hand is released from the valve control handle, said valve will return to a neutral position to hold pressure in said pressure line 147 and the cylinder 56 and to permit fluid to by-pass from the pressure line 123 through said valve to the return.

Fluid pressure is released from either of said cylinders 55 or 56 by moving the valve control handle in one direction or another to a position between the neutral and full open positions of said valve, as has before been described with reference to the valve 134. Fluid leaking past the rotor of said valve is returned to the tank 101 through a drain line 150.

Since the coil springs 190, 190 return the control handle 187 to a neutral position as soon as the hand is removed therefrom, and since fluid under pressure passes through the valve 124 on one side of the machine, to the associated control valve 126 on the opposite side of the machine to the valve 129, to operate one of the forward jacks 17 or to pass through said valve 129 and return to the tank 101, and since said valves 124 and 126 may at the same time hold pressure on the desired associated high or low speed planetary operating cylinder, the high and low speeds of one planetary 31 can be controlled from the valve 124 on one side of the machine or from the valve 126 on the opposite side of the machine and the associated jack 17 can be operated during operation of the machine. The valves 134 and 136 being the same as, and being connected together in the same manner as the valves 124 and 126, can thus control operation of the other planetary 31, from either side of the machine. The fluid connections between the valves on opposite sides of the machine are thus so arranged that each valve is supplied with pressure whenever the hand is removed from the control handle of the valve on the opposite side of the machine, thus permitting the associated planetary operating cylinder to be charged or discharged from either side of the machine and permitting operation of the jacks 17, 17 during operation of the machine.

It may be seen from the foregoing that the valves 124, 126, 134 and 136 are so arranged that fluid under pressure may be supplied to operate the jacks 17, 17 when any one of said valves is in

a neutral position, holding pressure on an associated high or low speed friction band, thus permitting operation of said jacks while the machine is being positioned for cutting or is being fed across a working place during the cutting operation, and permitting the cutter bar to be readily accommodated to cut out a band of impurities, where the bottom does not conform thereto. It may further be seen that the foregoing arrangement of valves permits the two planetaries to be operated together or independently of each other at either high or low frictionally controlled speeds, and that said valves are so arranged as to prevent the engagement of the high and low speed friction bands of said planetaries at the same time.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

23 I claim as my invention:

1. In a fluid control system particularly adapted to control operation of a kerf-cutting machine having a projecting chain carrying cutter bar and having flexible feeding means for feeding said cutter bar across a coal face with means for operating said flexible feeding means at high and low speeds, a fluid pump, a tank, high and low speed fluid-operated control means for said feed operating means, two control valves for said fluid operated control means, each of which are adapted to control operation of said feed operating means at either a high or a low speed, one of said valves being on one side of the machine and the other of said valves being on the opposite side of the machine, a connection from said pump to one of said valves to supply fluid under pressure thereto, a connection from the discharge side of said one valve to the pressure side of said other valve, to supply fluid under pressure thereto, said valves being so constructed and arranged that when said valves are in a neutral position, said valves will hold pressure on either said high or said low speed fluid operated control means for said feed operating means, and fluid under pressure will pass through one of said valves to the other of said valves and will pass through the other of said valves to said tank, and means for returning said valves to a neutral position when the hand is removed from the operating handle thereof, to permit operation of said feed operating means by means of either of said valves from either side of the machine at either a high or a low speed.

2. In a fluid control system particularly adapted to control operation of a kerf-cutting machine having a projecting chain carrying cutter bar and having flexible feeding means for feeding said cutter bar across a coal face with means for operating said flexible feeding means at high and low speeds, a fluid pump, a tank, high and low speed fluid operated control means for said feed operating means, two control valves for said fluid operated control means, each of said valves having an operating handle adapted to operate said valve and control operation of said feed operating means at either a high or low speed, one of said valves being on one side of the machine and the other of said valves being on the opposite side of the machine, a connection from said pump to one of said valves to supply fluid under pressure there-

to, a connection from the discharge side of said one valve to the pressure side of said other valve, to supply fluid under pressure to said other valve through said one valve, said valves being so constructed and arranged that when said valves are in a neutral position, said valves will hold pressure on either said high or said low speed fluid operated control means for said feed operating means, and fluid under pressure will pass through one of said valves to the other of said valves and will pass through the other of said valves to said tank, and spring means having operative connection with said operating handles of said valves, for returning said valves to a neutral position when the hand is removed from the operating handle thereof, to permit operation of said feed operating means by means of either of said valves, from either side of the machine, at either a high or a low speed.

3. In a fluid control system particularly adapted to control operation of a kerf-cutting machine having a projecting cutter chain carrying cutter bar with flexible feeding means for feeding said cutter bar across a coal face and means for operating said flexible feeding means at high and low speeds, a fluid storage tank, a fluid pump, fluid pressure operating means for controlling operation of said feed operating means at either a high or low speed including a fluid pressure cylinder and piston for controlling operation of said feed operating means at a high speed, another fluid pressure cylinder and piston for controlling operation of said feed operating means at a low speed, two control valves for controlling operation of said high and low speed controlling cylinders and pistons, one of said valves being on one side of the machine and the other of said valves being on the opposite side of the machine, a pressure connection from said pump to one of said valves, a connection from the exhaust side of said one valve to the pressure side of said other valve, for supplying fluid under pressure to said other valve through said first mentioned valve, a return connection from said other valve to said tank, a common fluid connection between said valves and said high speed controlling cylinder, a common fluid connection between said valves and said low speed controlling cylinder, so arranged that either of said valves may supply fluid under pressure to either of said cylinders, or may hold pressure therein, said valves each being so arranged that either of said valves will supply fluid under pressure to one of said cylinders when in one position and will exhaust fluid therefrom when in another position, and will hold pressure in said cylinders when in a neutral position, and so fluid will pass from one valve to the other when in a neutral position, so the operation of said feed operating means can be controlled from either side of the machine.

4. In a fluid control system particularly adapted to control operation of a kerf-cutting machine having a projecting cutter chain carrying cutter bar with flexible feeding means for feeding said cutter bar across a coal face and means for operating said flexible feeding means at high and low speeds, a fluid storage tank, a fluid pump, fluid pressure operating means for controlling operation of said feed operating means at either a high or low speed including a fluid pressure cylinder and piston for controlling operation of said feed operating means at a high speed, another fluid pressure cylinder and piston for controlling operation of said feed operating means at a low speed, two control valves for controlling opera-

tion of said high and low speed controlling cylinders and pistons, one of said valves being on one side of the machine and the other of said valves being on the opposite side of the machine, a pressure connection from said pump to one of said valves, a connection from the exhaust side of said valve to the pressure side of said other valve, for supplying fluid under pressure to said other valve through said first mentioned valve, a return connection from said other valve to said tank, a common fluid connection between said valves and said high speed controlling cylinder, a common fluid connection between said valves and said low speed controlling cylinder, so arranged that either of said valves may supply fluid under pressure to either of said cylinders, or may hold pressure therein, said valves each being so constructed and arranged that either of said valves will supply fluid under pressure to one of said cylinders when in one position and will exhaust fluid therefrom when in another position, and will hold pressure in the desired cylinder when in a neutral position, and means for returning said valves to a neutral position the instant the hand is removed from the operating handle thereof, so fluid under pressure will pass from one valve to the other, to permit operation of said feed operating means from either side of the machine.

5. In a fluid control system particularly adapted to control operation of a kerf-cutting machine having a projecting cutter chain carrying cutter bar with flexible feeding means for feeding said cutter bar across a coal face and means for operating said flexible feeding means at high and low speeds, a fluid storage tank, a fluid pump, fluid pressure operating means for controlling operation of said feed operating means at either a high or low speed including a fluid pressure cylinder and piston for controlling operation of said feed operating means at a high speed, another fluid pressure cylinder and piston for controlling operation of said feed operating means at a low speed, two control valves for controlling operation of said cylinders and pistons, one of said valves being on one side of the machine and the other of said valves being on the opposite side of the machine and each of said valves having an operating handle for controlling operation thereof, a pressure connection from said pump to one of said valves, a connection from the exhaust side of said valve to the pressure side of said other valve, for supplying fluid under pressure to said other valve through said first mentioned valve, a return connection from said other valve to said tank, a common fluid connection between said valves and said high speed controlling cylinder, a common fluid connection between said valves and said low speed controlling cylinder, so arranged that either of said valves may supply fluid under pressure to either of said cylinders, or may hold pressure therein, said valves each being so constructed and arranged that either of said valves will supply fluid under pressure to one of said cylinders when in one position and will exhaust fluid therefrom when in another position, and will hold pressure in the desired cylinder when in a neutral position, and spring means having engagement with said operating handles for returning said valves to a neutral position when the hand is removed from the control handle thereof, so fluid under pressure will pass from one valve to the other, to permit operation of said feed operating means from either side of the machine.

6. In a fluid control system particularly adapted to control operation of a kerf-cutting machine having a projecting cutter chain carrying cutter bar with flexible feeding means for feeding said cutter bar across a coal face, a plural speed planetary geared reduction device for operating said flexible feeding means, said planetary geared reduction device having a high speed friction band and a low speed friction band, for controlling operation thereof, to cause said planetary to drive said feed operating means at either a high or a low speed, a fluid pressure cylinder and piston for applying said high speed friction band, a fluid pressure cylinder and piston for applying said low speed friction band, a fluid storage tank, a pump, two control valves for controlling operation of said cylinders and pistons, said valves being on opposite sides of the machine, and each of said valves being adapted to selectively supply fluid to both of said cylinders, a fluid connection from said pump to one of said valves, a connection from the exhaust side of said one valve to the pressure side of said other valve, for supplying fluid under pressure to said other valve through said first valve, a return connection from said other valve to said tank, a common fluid connection from said valves to said high speed controlling cylinder, a common fluid connection from said valves to said low speed controlling cylinder, said valves being so constructed and arranged that either of said valves may supply fluid under pressure to one of said cylinders when moved in one direction into one position and will exhaust fluid therefrom when moved in another direction into another position, and will hold pressure in the desired cylinder when moved to a neutral position, and means operable to return said valves to a neutral position the instant the hand is removed from the operating handle thereof, so fluid under pressure will pass from one valve to the other, to permit operation of said planetaries from either side of the machine.

7. In a fluid control system particularly adapted to control operation of a kerf-cutting machine having a projecting cutter chain carrying cutter bar with flexible feeding means for feeding said cutter bar across a coal face, a plural speed planetary geared reduction device for operating said flexible feeding means, said planetary geared reduction device having a high speed friction band and a low speed friction band, for controlling operation thereof, to cause said planetary to drive said feed operating means at either a high or a low speed, a fluid pressure cylinder and piston for applying said high speed friction band, a fluid pressure cylinder and piston for applying said low speed friction band, a fluid storage tank, a pump, two control valves for controlling operation of said cylinders and pistons, said valves being on opposite sides of the machine, and each of said valves being adapted to selectively supply fluid to both of said cylinders, a fluid connection from said pump to one of said valves, a fluid connection from said one valve to said other valve, for supplying fluid under pressure to said other valve through said first valve, a return connection from said other valve to said tank, a common fluid connection from said valves to said high speed controlling cylinder, a common fluid connection from said valves to said low speed controlling cylinder, said valves each having a pivotally movable operating handle for controlling operation thereof and being so constructed and arranged that either of said valves may supply fluid under pressure to

one of said cylinders when turned in one direction and will exhaust fluid therefrom when turned in another direction, and will hold pressure in the desired cylinder when turned to a neutral position, and spring means engageable with said operating handles and operable to pivot said operating handles to return said valves to a neutral position when the hand is removed therefrom, so fluid under pressure will pass from one valve to the other, to permit operation of said planetaries from either side of the machine.

8. In a fluid control system particularly adapted to control operation of a kerf-cutting machine having a projecting cutter chain carrying cutter bar with flexible feeding means for feeding said cutter bar across a coal face, a plural speed planetary geared reduction device for operating said flexible feeding means, said planetary geared reduction device having a high speed friction band and a low speed friction band, for controlling operation thereof, to cause said planetary to drive said feed operating means at either a high or a low speed, a fluid pressure cylinder and piston for applying said high speed friction band, a fluid pressure cylinder and piston for applying said low speed friction band, a fluid storage tank, a pump, two control valves for controlling operation of said cylinders and pistons, said valves being on opposite sides of the machine, and each of said valves being adapted to selectively supply fluid to both of said cylinders, a fluid connection from said pump to one of said valves, a fluid connection from said one valve to said other valve, for supplying fluid under pressure thereto, a return connection from said other valve to said tank, a common fluid connection from said valves to said high speed controlling cylinder, a common fluid connection from said valves to said low speed controlling cylinder, so arranged that either of said valves may supply fluid under pressure to either of said cylinders, or may hold pressure therein, said valves being so arranged that either of said valves will supply fluid under pressure to one of said cylinders when turned to one position in one direction and will exhaust fluid therefrom when turned to one position in an opposite direction, and will supply fluid under pressure to the other of said cylinders when turned to one position in one direction and will exhaust fluid from said other cylinder when turned to another position in an opposite direction, and both of said valves will hold pressure in the charged cylinder when in a neutral position, and said valves being arranged so that fluid will pass from one valve through the other to said tank, when in a neutral position, so the operation of said friction bands can be controlled from either side of the machine.

9. In a fluid control system particularly adapted to control operation of a kerf-cutting machine having a projecting cutter chain carrying cutter bar with flexible feeding means for feeding said cutter bar across a coal face, a plural speed planetary geared reduction device for operating said flexible feeding means, said planetary geared reduction device having a high speed friction band and a low speed friction band, for controlling operation thereof, to cause said planetary to drive said feed operating means at either a high or a low speed, a fluid pressure cylinder and piston for applying said high speed friction band, a fluid pressure cylinder and piston for applying said low speed friction band, a fluid storage tank, a pump, two control valves for controlling operation of said cylinders and pistons,

said valves being on opposite sides of the machine, and each of said valves being adapted to selectively supply fluid to both of said cylinders, a fluid connection from said pump to one of said valves, a fluid connection from said one valve to said other valve, for supplying fluid under pressure thereto, a return connection from said other valve to said tank, a common fluid connection from said valves to said high speed controlling cylinder, a common fluid connection from said valves to said low speed controlling cylinder, so arranged that either of said valves may supply fluid under pressure to either of said cylinders, or may hold pressure therein, said valves being so arranged that either of said valves will supply fluid under pressure to one of said cylinders when turned to one position in one direction and will

5 exhaust fluid therefrom when turned to one position in an opposite direction, and will supply fluid under pressure to the other of said cylinders when turned to one position in one direction and will 10 exhaust fluid from said cylinder when turned to another position in an opposite direction and both of said valves will hold pressure in the charged cylinder when in a neutral position, and so fluid will pass from one valve through the 15 other to said tank, when in a neutral position, and means for returning said valves to a neutral position when the hand is removed from the control handle thereof, so fluid under pressure will pass from one valve to the other, to permit operation of said planetaries from either side of the machine.

WILLIAM W. SLOANE.
